UNITED STATES PATENT OFFICE.

ALEXIS JOSEPH JULLIN, OF ST.-CLOUD, FRANCE.

APPARATUS FOR REGULATING THE VOLTAGE OF DYNAMO-ELECTRIC MACHINES.

1,421,246.

Specification of Letters Patent. Patented June 27, 1922.

Application filed May 20, 1920. Serial No. 382,921.

(GRANTED UNDER THE PROVISIONS OF THE ACT OF MARCH 3, 1921, 41 STAT. L., 1313.)

To all whom it may concern:

Be it known that I, ALEXIS JOSEPH JULLIN, citizen of the Republic of France, residing at 14 Rue de Garches, St.-Cloud, Seine et Oise, in the Republic of France, have invented new and useful Improvements in Apparatus for Regulating the Voltage of Dynamo-Electric Machines, (for which I have filed an application in France April 30, 1918, 10 Patent No. 505,700), of which the following is a specification.

This invention has for its object to provide an improved apparatus for regulating the voltage of dynamos running at varying 15 speeds and under varying loads, more particularly employed for the lighting of vehicles.

The improved apparatus is characterized chiefly by the feature that it comprises a 20 vibrating tongue actuated by the attraction of a solenoid whose field is influenced by the variations in the voltage of the dynamo, and is pulled back by a spring. This vibrating tongue is capable of touching one or other of 25 two contacts connected at points situated at different potentials in such a manner as to establish circuits including the vibrating tongue, suitable resistances and a single regulating inducing coil for influencing the 30 citation of the dynamo, the said circuits being such that this regulating inducing coil is thus traversed in consequence of the vibrations of the vibrating tongue, by an undulating current whose mean value will produce the necessary excitation for obtaining 35 the desired voltage.

In the case of a given dynamo, the range of possible regulation is increased by employing a double-contact regulator instead 40 of a known type of single-contact regulator.

The use of the double-contact under the hereinafter described conditions allows also of going as far as the reversal of the current in the single exciting coil when this is 45 necessary, as for instance in the case of the working of a "Rosenberg" dynamo of limited voltage with compensation for the armature reaction, or in the case of the working of a step-up and step-down machine.

50 In the accompanying drawings given by way of example:—

Fig. 1 is a diagram of a constructional form of the improved regulating apparatus forming the subject matter of this invention,

wherein the pivot of the vibrating tongue is 55 connected to one end of the inducing winding.

Fig. 2 is a partial diagram illustrating the actuation of the vibrating tongue by a 60 relay.

Fig. 3 illustrates an apparatus wherein one end of the inducing winding is connected to a supplementary brush rubbing on the dynamo commutator or collector ring.

Figs. 4, 5, 6, and 7 illustrate apparatus 65 which are analogous to those shown in Fig. 1, but comprise slight modifications.

Fig. 8 illustrates an apparatus wherein the pivot of the vibrating tongue is connected to one of the terminals of the dynamo. 70

Fig. 9 illustrates the general scheme of the application of any one of the above mentioned apparatus, allowing of reversing the current in the regulating inducing coil, in the case of a dynamo comprising already 75 another coil which may be either a shunt excitation coil or an independent excitation coil.

Fig. 10 illustrates likewise by way of example the application of one of the above 80 mentioned apparatus for the regulation of an installation with storage battery, comprising a step-up and step-down transformer inserted in the exciting circuit.

The improved apparatus illustrated dia- 85 grammatically in Fig. 1, comprises a dynamo whose armature is indicated at 21 and whose terminals are designated by A, B; 22 is its inducing coil whose terminals are designated by C, D; 23, 24 are the two portions 90 of a resistance connected to the dynamo terminals; 26, 27^a, 27^b, 28 are the different portions of another resistance or of separate resistances arranged in series and connected likewise to the terminals of the dynamo or 95 to the circuit supplied by the latter; 29 is a tongue adapted to vibrate between the contacts E, F which are connected in their turn respectively to the junction points of the resistances 26 and 27^a, 27^b and 28; 30 is a condenser connected to the terminals of the coil 22; 36 is the external circuit (comprising for instance lamps); 37 is a storage battery which may be provided or not, and which in the former case is coupled to the 100 dynamo by means of an automatic switch (not shown) when the voltage of the said dynamo has attained a suitable value. 105

The vibrating tongue 29 is pulled back by a spring 7 and is attracted by a solenoid 4 which is mounted in series with a regulating resistance 5 in a branch circuit connected to 5 the terminals of the dynamo or of the net.

The solenoid 4 is suitable on the other hand in the case of low power dynamos or 10 dynamos whose exciting circuits are designed to bring only weak currents into action. For other machines it is advisable to actuate the 15 vibrating tongue 29 through the medium of one or more relays. Fig. 2 shows how the vibrating tongue 29 may be actuated by a relay 4' which is in its turn actuated by the main solenoid 4.

The operation of the described apparatus is as follows (see Fig. 1) :—

For the sake of clearness it is assumed that A is the positive pole of the dynamo and B 20 the negative pole of the dynamo.

The arrangement and adjustment are such that for a given speed and for a given load on the dynamo, the mean current flowing (for instance in the direction D C) in the 25 field magnet windings shall have the requisite value for generating the desired voltage. To every increase in the voltage due to any cause (increase of speed or diminution of load) there will correspond an 30 increase of the current and consequently of the attraction of the coil of the main solenoid, which will have for effect, either directly or through the medium of the coil of the relay, to cause the tongue 29 to make 35 contact with the contact piece F. The establishment of this contact will produce a diminution in the exciting current, since, according to the assumption made above as to the polarities, the potential at the point F 40 is lower than that at the point E. The reverse will take place for every diminution in the voltage, so that a variation in the excitation opposing the variation in the voltage will follow the latter immediately. The 45 result is a series of oscillations or vibrations of the tongue 29 which will have a tendency to increase the duration of the intermittent periods of contact on the E side or on the F side to the detriment of the duration of the 50 contacts at the opposite side according as the excitation is to be reinforced or diminished.

The result of the foregoing will be the establishment in the field magnet windings, 55 of an undulating current whose mean value will correspond to the excitation that is necessary to generate the desired voltage (it may happen that the tongue will vibrate only against one of the contacts without touching the other contact, such one-sided vibration taking place on one side or the other according to the direction of the regulation).

It is to be noted that in the preceding arrangement, the resistance sections 23 and 60 26—27^a on the one hand, and 24 and 27^b—28

on the other hand, constitute discharging circuits for the field magnet winding whose self-induction, showing itself in the form of 70 sparking at the contacts, can thus be largely diminished.

The provision of the condenser 30 completes the arrangement of the discharging 75 circuits for the same purpose.

Instead of connecting one of the ends of the field magnet winding at the junction C 80 of two resistance sections 23 and 24 as shown in Fig. 1, the said end may be connected either to a supplementary brush rubbing on the commutator or collector ring of the dynamo between the two main brushes, 85 or to a revolving ring connected to any point of the armature or finally to an intermediate point of the storage battery.

Fig. 3 illustrates the arrangement in the 90 first of the above mentioned cases. The other two arrangements (wherein the current is taken from a ring or from a battery) can be readily imagined.

Figs. 4 and 5 illustrate modifications of the preceding arrangements. In these 95 figures 32 and 33 represent supplementary discharge resistances the provision of which is intended for use in installations of considerable power.

In all the apparatus hereinbefore described the resistances shown in the figures must have the values that are suitable for each particular case. Some of these resistances may be of thousands of ohms or they 100 may be infinitely great, and their combinations may lead in reality to numerous special arrangements.

Figs. 6 and 7 illustrate by way of example 105 modifications of the general arrangement of Fig. 1 wherein the resistances 24—26 are nil, and the resistance 23 is infinitely great. In Fig. 6, 32 and 33 indicate the supplementary discharge resistances and in Fig. 7, 34 and 35 indicate resistances interposed 110 in conductors that are connected to the contacts E F so as to avoid sparking between these two contacts in the case where the high difference of potential between the ends of the resistance 27 would have a tendency to cause such sparking.

The arrangements of Figs. 6 and 7 do not however allow of regulating as far as the reversal of the current in the field magnet windings as can be done in the arrangements shown in the foregoing figures.

Furthermore, instead of a single condenser 30 connected to the terminals of the field magnet winding, one of these devices may be mounted in the ordinary manner between the movable tongue and each of the 120 contacts E and F.

Fig. 8 illustrates another arrangement 125 which allows of utilizing the double contact with a single coil and extending the possibility of regulation to such an extent

as to effect a reversal of the current in the said coil, without it being necessary to take current from an intermediate point from the dynamo, from the battery or from auxiliary resistances connected to the dynamo terminals as in the foregoing cases. In this Fig. 8, 41 is the dynamo armature; 42 is the inducing winding whose terminals G H are connected by leads to the fixed contacts I J between which can vibrate the tongue 43 which is connected at K to one of the poles of the dynamo; 44, 45, 46 and 47 represent resistances connected at one end to the terminals G H of the winding 42 and at their other ends to the points L K connected respectively to the two poles of the dynamo or of the external circuit (the resistances 46, 47 may be absent in certain cases). 48 is a condenser connected to the terminals of winding 42.

The vibrations of the tongue 43 are produced in the same manner as those of the tongue 29 in the case illustrated in Fig. 1 which has been hereinbefore described in detail, giving analogous effects. These effects thus generate in the winding 42 an undulating current whose mean value corresponds to the excitation that is required for producing the desired voltage.

Fig. 9 shows the general arrangement of the application of any one of the above mentioned arrangements, allowing of reversing the current in the regulating inducing winding is the case of a dynamo comprising another winding either for shunt excitation or for independent excitation.

In this figure, 61 is the armature; 62 is a shunt-inducing winding; 63 is an inducing winding for regulating up to reversal of the current connected to the resistance bridge of the regulator according to one of the arrangements above described (to render the case more general this bridge is represented by the entity 64 shown in dotted lines). 65 is the external circuit.

It will be seen for example that if matters are so regulated as to cause the voltage to remain substantially constant at the dynamo terminals, the winding 62 will produce a substantially constant field. But the winding 63, subjected to the action of the regulator, will be traversed by a variable current in one direction or the other, and this current will generate a field that will reinforce the first field or will be in opposition to it to the amount necessary for requirement.

Fig. 10 illustrates likewise by way of example, the application of one of the above mentioned arrangements for regulating an installation having a storage battery, comprising a step-up and step-down device included in the exciting circuit. In this figure, 71 is a dynamo armature; 72 are the

shunt exciting coils of the latter; 73 is a regulating resistance; 74 is the armature of the step-up and step-down device; 75 are the exciting coils of the latter connected to the resistance bridge of the regulator according to one of the above described arrangements, and which for the sake of more general application, is represented in dotted lines as an entity 76; 77 is the storage battery; 78 is the automatic cut-out switch; 79 is the external circuit.

It is to be understood that matters may be so regulated that for instance with a medium speed and load of the dynamo, the current flowing in the winding 75, and consequently the voltage at the terminals of the small armature 74, will be substantially nil. Then the normal voltage at the dynamo terminals will alone determine the normal exciting current of the exciting windings 72 for the specified working. According as a diminution or an increase of voltage will tend to become established at the terminals of the dynamo (by the action of the variations in the speed and in the load) a current will be generated in the winding 75 which will cause the armature 74 to act as a step-up or as a step-down device respectively to the dynamo voltage in the circuit of the exciting windings of the dynamo, with the result of increasing or diminishing the exciting current of the latter; and this effect will oppose a variation of the initial voltage.

Having now described my invention, what I claim as new and desire to secure by Letters Patent is:

1. An apparatus for regulating the voltage of dynamos running at varying speeds and under varying loads, comprising a solenoid controlled by the voltage of the dynamo, a vibrating tongue controlled by said solenoid a spring controlling said vibrating tongue, two contact members adapted to cooperate with said vibrating tongue, an exciting winding for the dynamo, and two open electric circuits influenced by the voltage of the dynamo, embodying predetermined resistances, and respectively connecting said contact members to the dynamo terminals, each of said open circuits being adapted to be closed by said vibratory tongue and said exciting winding for the dynamo.

2. An apparatus for regulating the voltage of dynamos running at varying speeds and under varying loads, comprising a solenoid adapted to be controlled by the voltage of the dynamo, a relay controlled by the voltage of the dynamo and adapted to put said solenoid into circuit, a vibrating tongue controlled by said solenoid, a spring controlling said vibrating tongue, two contact members adapted to cooperate with said vibrating tongue, an exciting winding for the dynamo, and two open electric circuits influenced by

the voltage of the dynamo, embodying predetermined resistances, and respectively connecting said contact members to the dynamo terminals, each of said open circuits being 5 adapted to be closed by said vibratory tongue and said exciting winding for the dynamo.

3. An apparatus for regulating the voltage of dynamos running at varying speeds and 10 under varying loads, comprising a solenoid controlled by the voltage of the dynamo, a vibrating tongue controlled by said solenoid, a spring controlling said vibrating tongue, two contact members adapted to cooperate 15 with said vibrating tongue, an exciting winding for the dynamo, electric connections embodying predetermined resistances for respectively connecting the ends of said exciting winding to one terminal of the dynamo, means for connecting the ends of said exciting winding to the said contact members and 20 means for connecting the pivot of the vibrating tongue to the other terminal of the dynamo.

4. An apparatus for regulating the voltage of dynamos running at varying speeds and under varying loads, comprising a solenoid controlled by the voltage of the dynamo, a vibrating tongue controlled by said solenoid, 25 a spring controlling said vibrating tongue, two contact members adapted to cooperate with said vibrating tongue, an exciting winding for the dynamo, electric connections 30 embodying predetermined resistances for respectively connecting the ends of said exciting winding to one terminal of the dynamo, means for connecting the ends of said exciting winding to the said contact members and means for connecting the pivot of the vibrating tongue to the other terminal of the dynamo.

5. An apparatus for regulating the voltage of dynamos running at varying speeds and under varying loads, comprising a solenoid controlled by the voltage of the dynamo, a vibrating tongue controlled by said solenoid, 35 a spring controlling said vibrating tongue, two contact members adapted to cooperate with said vibrating tongue, an exciting winding for the dynamo, electric connections embodying predetermined resistances 40 for connecting respectively said contact members to the terminals of the dynamo, means for connecting one end of said excit-

ing winding to the pivot of the vibrating tongue and means for subjecting the other end of said exciting winding to a voltage 45 lower than that of the dynamo.

6. An apparatus for regulating the voltage of dynamos running at varying speeds and under varying loads, comprising a solenoid controlled by the voltage of the dynamo, a 50 vibrating tongue controlled by said solenoid, a spring controlling said vibrating tongue, two contact members adapted to cooperate with said vibrating tongue, an exciting winding for the dynamo, electric connections embodying predetermined resistances for respectively connecting the ends of said exciting winding to one terminal of the dynamo, means for connecting the ends of said exciting winding to the said contact members and 55 means for connecting the pivot of the vibrating tongue to the other terminal of the dynamo.

7. An apparatus for regulating the voltage of dynamos running at varying speeds and under varying loads comprising a solenoid controlled by the voltage of the dynamo, a vibrating tongue controlled by said solenoid, a spring controlling said vibrating tongue, two contact members adapted to 60 cooperate with said vibrating tongue, an exciting winding for the dynamo; and two open electric circuits influenced by the voltage of the dynamo, embodying predetermined resistances, and respectively connecting said 65 contact members to the dynamo terminals, each of said open circuits being adapted to be closed by said vibratory tongue and said exciting winding for the dynamo, and a condenser shunted over the ends of said exciting 70 winding.

In testimony whereof I have signed my name to this specification.

ALEXIS JOSEPH JULLIN.
